FOUNDATION GARMENT

Mario Laguzzi, Long Island City, N.Y., assignor to Poirette Corsets, Inc., New York, N.Y.

Filed Jan. 31, 1962, Ser. No. 68,594

Term of patent 14 years

(Cl. D20—2)

I claim:

The ornamental design for a foundation garment, as shown and described.
